(57) **CLAIM**

The ornamental design for a shoe, as shown and described.

DESCRIPTION

FIG. 1 is a front perspective view of a shoe showing my new design;
FIG. 2 is a side view thereof;

FIG. 3 is a rear perspective view thereof;

FIG. 4 is an opposite side rear perspective view thereof; and,
FIG. 5 is an opposite side view thereof.

The broken lines immediately adjacent to the shaded area define the bounds of the claimed design and form no part thereof. The four broken line shapes and the unshaded areas therein represent regions that form no part of the claimed design. The broken lines depicting the remainder of the shoe form no part of the claimed design.
